(57) CLAIM

The ornamental design for an electric meat grill, as shown and described.

DESCRIPTION

1. Electric meat grill

FIG. 1.1 is a perspective view of an electric meat grill showing the new design.

FIG. 1.2 is a right side view thereof.

FIG. 1.3 is a rear view thereof.

FIG. 1.4 is a left side view thereof.

FIG. 1.5 is a front view thereof.

FIG. 1.6 is a top view thereof.

FIG. 1.7 is a perspective view of the electric meat grill shown in an alternate open configuration.

The broken lines in the drawings depict portions of the electric meat grill that form no part of the claimed design.

1 Claim, 7 Drawing Sheets(56)
